UNITED STATES PATENT OFFICE.

ABRAM ALLAN HENDRICKSON, OF ORADELL, NEW JERSEY.

MASSAGE APPARATUS.

Application filed March 28, 1928. Serial No. 265,464.

The present invention is concerned with the provision of a device which may be conveniently used for accomplishing an efficient self-massage of practically any part of the body. A secondary function of the apparatus is its possible use as an exerciser.

The device is of the type in which an elongated flexible member is provided with handles at its ends and with massaging rollers or similar elements at its intermediate portions. It is used by grasping the handles with the two hands, and reciprocating the massaging elements across the portion of the body which is to be massaged. By use of the device, an extremely invigorating massage may be had, and the device is quite efficient in reducing weight, in that it effectively breaks down much of the fatty tissue in the area being massaged.

20 Prior devices of this general character have been subject to one material disadvantage, which is the fact that they were ill suited to meet sanitary requirements, and could not be washed without injury.

25 In accordance with the present invention I have provided a massaging device of this character having no metal parts, and no parts which can be rusted or otherwise injured by the action of soap and water. In consequence, 30 the entire device may be conveniently washed or sterilized and may further be safely brought into intimate contact with the various parts of the user's body to be treated.

Another material advantage of the present 35 invention is the fact that I provide a device having no projecting parts which might scratch, cut, or otherwise injure the user's body. The parts of the massage apparatus which are manually grasped, and the parts 40 which are rolled or rubbed across the body are devoid of projections or sharp edges which might injure either the body or the hands.

45 Other and more general objects of the invention are to provide a massage apparatus of simple, practical construction, which will be rugged, durable and efficient in use, and well suited to the requirements of economical manufacture and convenient manipulation.

50 With the above noted and other objects in view, the invention consists in certain novel features of construction and combination and arrangements of parts as will be more fully hereinafter set forth and pointed out in the claims. The invention may be more fully understood from the following description in

connection with the accompanying drawings, wherein—

Fig. 1 is a broken view mainly in plan and partly in section through a massage device 60 embodying the invention.

Fig. 2 is an edge view of Fig. 1, taken approximately on the line 2—2 thereof.

Fig. 3 is a fragmentary view similar to Fig. 1, but showing a slight modification. 65

In the drawings I have used the reference numeral 10—10 to designate a pair of parallel handles, the ends of which are connected by pairs of parallel flexible devices 11 preferably comprising lengths of inelastic tape. The 70 handles 10 are preferably cut away or grooved at 12 to receive the tape and prevent the tape from slipping off the ends of the handle. Each tape comprises two overlying laminations, and the two thicknesses of tape are 75 sewed together by a plurality of lines of transverse stitching 13; the spaces between the stitching serving as pockets 14 receiving the reduced portions 15 of axles 16 for massage rollers 17. Any suitable number of the 80 rollers may be mounted upon each axle, being restrained against endwise movements by the tapes 11, but being freely rotatable on the axles. 85

When the two handles are grasped, the 85 massage elements placed in contact with the body, and the entire device reciprocated by pulling it first in one direction and then in the other, as will be readily understood, a very invigorating and effective massage may be 90 had.

95 Preferably, no metal parts are used in the construction. The axles, massage rollers, and handles are of wood or other non metallic material and the entire device may be readily washed or sterilized.

Considered from a structural standpoint, numerous expedients might be resorted to in the form of axle-receiving pockets 14, and numerous non-metallic materials might be 100 used to constitute the balls and cross pieces.

In Fig. 3, I have shown a slight modification of the invention in which pairs of side tapes 20 are connected to end handles 21. Adjacent the handles, side tapes 20 are connected by cross pieces 22 serving to anchor the ends of an intermediate flexible tape 23 disposed in parallelism with the tapes 20 and spaced therefrom. Here, the roller axles 24 are engaged by all three tapes and held 110 against axial displacement thereby, and massaging balls or equivalent elements 25 are

arranged on the exposed portions of the axles between the tape 23 and each side tape 20.

Obviously, various changes and alterations might be made in the general form and arrangement of the parts described without departing from the invention. Hence I do not wish to limit myself to the details set forth, but shall consider myself at liberty to make such changes and alterations as fairly fall within the spirit and scope of the appended claims.

I claim:

1. A massage device of the class described including a pair of handles, spaced parallel flexible devices connecting the handles, transversely disposed axles, the ends of which are secured to the flexible devices and massaging rollers mounted on the axles, the flexible devices comprising lengths of tape and the roller handles and axles being of wood.
2. A massage device of the class described including a pair of handles, spaced parallel flexible devices connecting the handles, transversely disposed axles, the ends of which are

secured to the flexible devices and massaging rollers mounted on the axles, the flexible devices limiting endwise sliding movement of the rollers on the axles, and comprising tapes defining pockets rotatably receiving reduced portions of the axles to hold the latter against axial displacement.

3. A massage device of the class described including a pair of handles, spaced parallel flexible devices connecting the handles, transversely disposed axles, the ends of which are secured to the flexible devices and massaging rollers mounted on the axles, said flexible devices comprising tapes defining pockets rotatably receiving reduced portions of the axles to hold the latter against axial displacement, said pockets being formed by parallel lines of stitching joining the two overlying tape laminations which constitute each flexible device.

Signed at New York, in the county of New York and State of New York, this 27th day of March, 1928.

ABRAM ALLAN HENDRICKSON.
